ROCK DRILL

Albert Feucht, Garfield Heights, Ohio, assignor
to The Cleveland Rock Drill Company, Cleve-
land, Ohio, a corporation of Ohio

Application November 14, 1941, Serial No. 419,065

3 Claims. (Cl. 255—45)

This invention relates broadly to rock drills, but more particularly to an improved fluid operated feeding mechanism and mounting for a rock drill of the drifter type.

One object of this invention is to provide a support for a rock drill on which the drill may be moved out of the path of the longitudinal axis of the drill steel without necessitating the loosening of clamps or the like.

Another object of this invention is to produce a supporting and feeding mechanism for a rock drill enabling the drill to be set up in any desired position and fed to the work under the control of the operator, this novel assembly being simple in construction, strong, durable and efficient in operation.

Another object of this invention is to produce a rock drill feeding mechanism equipped with suitable valve means through which operation of the drill and its feeding mechanism can readily and conveniently be controlled by the operator.

Other objects and advantages more or less ancillary to the foregoing reside in the specific construction and aggroupment of the elements peculiar to this structure, as will become apparent from a more complete examination of this specification.

In the drawings:

Fig. 1 is a side elevational view of a rock drill assembly embodying the invention and shown in operative position.

Fig. 2 is an enlarged fragmentary elevational view of the connection between the rock drill and feeding mechanism.

Fig. 3 is a cross sectional view taken in a plane indicated by line 3—3 in Fig. 2.

Figs. 4 and 5 are cross sectional views taken through a plane indicated by line 4—4 in Fig. 3 and illustrating a throttle valve in different positions.

Figs. 6 and 7 are views corresponding to Figs. 4 and 5 respectively but taken in a plane indicated by line 6—6 in Fig. 3.

Fig. 8 is a cross sectional view taken in a plane indicated by line 8—8 in Fig. 3.

Fig. 9 is a view similar to Fig. 1 but showing the rock drill in inoperative position.

Fig. 10 is an enlarged cross sectional view taken in a plane indicated by line 10—10 in Fig. 9.

Referring to the drawings, 15 represents the cylinder of a rock drill having front housing 16 adapted to receive the shank of a drill steel 17 normally held in the drill by a retainer 18. At

the other end of the cylinder 15 there is a head 19 having adequate connections to receive an air hose 20 and a water hose 21, the latter being provided with a valve 22.

5 The drill above referred to is of the usual type well-known in this art and includes the usual piston reciprocable within the cylinder 15 for imparting impacts to the drill steel 17 in rapid succession, the drill steel being normally 10 rotated by a rotation mechanism also included either in the cylinder 15 or head 19.

Referring now more particularly to the invention, intermediate the ends of the cylinder 15 there is an integral boss or lateral projection 15 23 formed with a tapered bore 24 extending therethrough and adapted to receive the tapered end 25 of a feed piston rod 26, the boss 23 being secured in position on the rod by a nut 27. The piston rod 26 extends from the open end of a feed cylinder 28 wherein it is slidably mounted through a bushing 29 secured in the open end of the feed cylinder 28 by a retaining sleeve 30 screwed on the cylinder 28. The inner end of the piston rod 26 is reduced as at 31 to receive 25 piston 32 which rests against a tapered shoulder 33 formed on the rod 26 and is secured in position on the rod by a retainer 34 screwed within the rod 26. To assume a fluid tight joint between the piston 32 and cylinder 28, the former 30 carries packing rings 35 under which pressure fluid may be admitted through ports 36 which open in a common annular recess 37 having motive fluid supplied thereto by a passage 38 in a manner hereinafter explained. The piston rod 35 26 is also provided with a bore 39 which is closed adjacent the outer end of the rod near the nut 27 but extends through the reduced portion 31 wherein it is reduced in diameter as at 40. The retainer 34 mounted at the inner end of the rod 40 26 is also provided with a central port 41 in constant communication with the bores 40 and 39 for admitting and exhausting motive fluid to and from the cylinder 28 behind the piston 32, the adjacent end of the cylinder being closed 45 by a special plug 42.

Within the boss 23 extending laterally from the cylinder 15, the piston rod bore 39 is in communication with an annular groove 43 through a radial port 44.

50 Between the rod 26 and the cylinder 15 there is provided in the boss 23 of the cylinder 15 a cylindrical chamber 45 which is closed at one end by a removable plug 46, while the other end is opened through a relatively small bore 47. Rotatable within the valve chamber 45 there

is a feed control valve 48 having a shank 49 extending through the reduced bore 47 where it is adapted to receive a handle 50 secured in position by a nut 51. In the valve 48 there is a bore 52 from which leads a radial port 53 opening into a groove 54 provided on the peripheral wall of the valve within a vertical plane indicated by line 4-4 in Fig. 3. The groove 54 as shown in Figs. 4 and 5 tapers outwardly in a counterclockwise direction and is capable of registration with the annular recess 43 through a port 55. Longitudinally spaced from the groove 53 and specifically within a vertical plane passing through line 6-6 in Fig. 3 the peripheral wall of the valve 48 is provided with an exhaust groove 56 which also tapers outwardly but in a clockwise direction in Figs. 6 and 7. The groove 56 is capable of communication with the annular groove 43 through a port 57, and with an exhaust port 58 which extends from the valve to the atmosphere through the boss 23.

In the backhead 19 there is a throttle valve 59 rotatably mounted within a cylindrical chamber 60 and operable by a handle 61. Also leading from the chamber 60, and not controlled by the throttle valve 59, there is a passage 62 opening into the valve chamber 45 back of the feed control valve 48 through which pressure fluid may be supplied to the bore 52 of the feed valve 48.

Within the vertical plane passing through line 8-8 in Fig. 3, the boss 23 is provided with a bore 63 which is perpendicular to the center axis of the valve 48 and normally closed by a removable plug 64. In this bore is slidably mounted a spring pressed locking plunger 65 formed with a wedged shaped end 66 engageable with teeth 67 provided on the peripheral wall of the valve 48 for preventing accidental rotation of the valve.

Near its inner end, this feed cylinder 28 is provided with a vent 68 which extends to the atmosphere through the retainer 30 for venting the cylinder during the outward movement of the piston 32. This vent as the piston approaches the end of its outward movement is closed by the piston to form a dash pot action in the inner end of the feed cylinder for preventing impact of the piston against the bushing 29.

In practice the feed cylinder 28 is rigidly secured to a column 69 by a releasable clamp 70, the column 69 being set-up under compression between the floor and ceiling 71 and 72 respectively of the stope 73 of a mine. The clamp 70 is preferably mounted to the end of a cross arm, not shown, which in turn is detachably secured to the column 69 in a manner well-known in this art.

In the operation, when the parts are positioned, as shown in Fig. 1, pressure fluid from any suitable source of supply is admitted through the hose 20 into the chamber 60 and when the throttle valve 59 is open, pressure fluid is admitted to the cylinder 15 for imparting reciprocation to the rock drill piston which delivers impacts to the drill steel 17 for performing the work. Concurrently water may also be admitted to the drill steel through hose 21 controlled by the valve 22. From the chamber 60, the pressure fluid will also flow through the passage 62 into the valve chamber 45 and therefrom into the valve bore 52. When the feed control valve 48 is positioned as shown in Figs. 5 and 7, motive fluid from the valve bore 52 will flow through the

valve port 53 into the groove 54 and therefrom into the annular groove 43 through the port 55. From the annular groove 43, the motive fluid will be admitted into the outer end of the feed cylinder 28 through the piston radial port 44, its bores 39 and 40 and port 41 of retainer 34, thereby exerting pressure on the piston 32 for sliding the piston and its component rod 26 out of the stationary feed cylinder 28. The rock drill 15 being held stationary on the end of the piston rod 26 will be fed to the work and the drilling operation proceeded in the regular manner. During this forward movement of the piston 32, the air trapped within the feed cylinder ahead of the piston will exhaust therefrom through the vent 68 and after this vent is finally covered by the piston, the air trapped between the vent and the end of the feed cylinder or bushing 29 will act as a cushion to limit further forward movement of the piston rod 26 relative to its cylinder. At that time, the operator may simply close the throttle valve 61 and turn the feed control valve 48 in the position shown in Figs. 4 and 6.

In this new position of the feed control valve 48 the pressure fluid previously admitted into the other end of the feed cylinder 28 may now escape therefrom through the port 41, piston rod bores 40 and 39, radial port 44, annular groove 43 and port 57, this last port being connected to the exhaust port 58 through the valve groove 56 as shown in Fig. 6, while the inlet port 53 is now moved out of communication with the port 55, as clearly shown in Fig. 4. Exhaust of the motive fluid through the feed cylinder will enable the operator to pull the piston rod 26 and rock drill 15 rearwardly and after having opened the retainer 18, the rock drill may be swung into the position shown in Fig. 9, that is, out of the path of the central axis of the drill steel 17, thereby enabling the removal of the drill steel preparatory to the insertion of a longer drill steel into the hole partly drilled. Thereafter the rock drill 15 may again be swung in a position coaxial with the drill steel as shown in Fig. 1 and the throttle valve 59 and feed valve 48 again opened to resume the drilling operation.

During feeding motion of the drill steel motive fluid flowing to the outer end of the feed cylinder through the piston rod bore 40 will also be admitted under the packings 35 through the radial port 38, groove 37 and ports 36 for urging the packings against the inner wall of the feed cylinder 28 to assure a fluid tight joint between the piston and cylinder.

From the foregoing description, it will be understood that the rock drill 15 may be swung out of the path of the drill steel 17 without the necessity of loosening the clamp 70 or any other similar clamps heretofore incorporated in rock drill mountings, thereby assuring perfect alignment of the rock drill relative to the drill steel as well as reducing the time required for changing the drill steel. Furthermore, the feed control valve 48 being located adjacent to the throttle valve handle 61 enables the operator to control either of them without inconvenience, the feed being readily controlled by positioning the valve 48 into a more or less complete open position of the groove 54 relative to the port 55.

Although the foregoing description is necessarily of a detailed character, in order to completely set forth the invention, it is to be understood that the specific terminology is not intended to be restrictive or confining and it is to be further understood that various rearrange-

ments of parts and modifications of structural detail may be resorted to without departing from the scope or spirit of the invention as herein claimed.

I claim:

1. In a rock drill mounting, a feeding mechanism including a feed cylinder, means for rigidly supporting said cylinder from the ground, a fluid actuated piston rod slidable and rotatable in said cylinder, a fluid actuated drilling motor, an integral projection for said motor extending laterally thereof, said projection having a tapered bore for clamping one end of said piston rod whereby the motor is carried by the feeding mechanism in offset relation with the center axis thereof, said piston rod having a bore extending throughout its length and a port communicating therewith, an annular recess formed in said tapered bore having communication with said port, and a feed valve carried by said projection for controlling the admission of motive fluid to said piston rod through said annular recess to operate said feeding mechanism.

2. In a rock drill mounting, a feeding mechanism including a feed cylinder, means for rigidly supporting said cylinder from the ground, a fluid actuated piston rod slidable and rotatable in said cylinder, a fluid actuated drilling motor, an integral projection for said motor extending laterally thereof, said projection having a tapered bore for clamping one end of said piston rod whereby the motor is carried by the feeding mechanism in offset relation with the center axis

thereof, the other end of said piston rod being of reduced diameter and carrying a piston thereon, a bore through said rod for admitting and exhausting fluid to and from said piston, a port in said rod communicating with said bore, an annular recess formed in said tapered bore having communication with said port, and a feed valve carried by said projection between said drill motor and cylinder for controlling the admission of motive fluid to said piston rod through said annular recess.

3. In a rock drill mounting, a feeding mechanism including a feed cylinder, means for rigidly supporting said cylinder from the ground, a fluid actuated piston rod slidable and rotatable in said cylinder, a fluid actuated drilling motor, an integral projection for said motor extending laterally thereof, said projection having a tapered bore for clamping one end of said piston rod whereby the motor is carried by the feeding mechanism in offset relation with the center axis thereof, said piston rod having a bore extending throughout its length and a port communicating therewith, a chamber in said projection between said motor and cylinder, a feed valve mounted for rotation in said chamber having a fluid receiving recess, inlet and exhaust ports formed in the periphery of said valve adapted to be brought into registry with said port for admitting fluid to said feeding mechanism, and means for controlling said valve.

ALBERT FEUCHT.
